UNITED STATES PATENT OFFICE.

JOHN J. McGRANE, OF NEW YORK, N. Y.

DESIGN FOR A HOME-SHRINE.

49,097.

Specification for Design.

Patented May 23, 1916.

Application filed February 3, 1916. Serial No. 76,056. Term of patent 3½ years.

To all whom it may concern:

Be it known that I, JOHN J. McGRANE, a citizen of the United States, and a resident of the city of New York, Elmhurst, borough of Queens, in the county of Queens, and State of New York, have invented a new, original, and ornamental Design for a Home-Shrine, of which the following is a specification, reference being had to the accompanying drawing, forming part thereof, in which the figure is a perspective view of a home-shrine, showing my new design.

The invention comprises a facade-like panel or niche, an image of the Virgin Mary and Child set in the niche, a cross surmounting the panel, and a lamp at the foot and in front of the image.

I claim:

The ornamental design for a home-shrine, as shown and described.

JOHN J. McGRANE.
